UNITED STATES PATENT OFFICE.

GEORGE PLINEY BOSWORTH, OF CENTRAL FALLS, RHODE ISLAND, ASSIGNOR TO HEMPHILL COMPANY, OF PAWTUCKET, RHODE ISLAND, A CORPORATION OF MASSACHUSETTS.

KNITTING MACHINE.

Application filed December 27, 1919. Serial No. 347,666.

To all whom it may concern:

Be it known that I, GEORGE PLINEY Bosworth, a citizen of the United States, and a resident of Central Falls, in the county of Providence and State of Rhode Island, have invented an Improvement in Knitting Machines, of which the following description, in connection with the accompanying drawings, is a specification, like characters on the drawings representing like parts.

This invention relates to knitting machines and more particularly, though not exclusively, to spring needle knitting machines, and is an improvement upon the invention disclosed in my Patent No. 1,490,908, Apr. 22, 1924, Serial No. 306,094, filed June 23, 1919.

In the accompanying drawings I have, merely for the purposes of illustration, disclosed a machine embodying the characteristics of my invention wherein:

Fig. 1 is a vertical section through the knitting head of the machine;

Fig. 2 illustrates in detail, and greatly enlarged, the relation of the web holder and needle at the time the web holder is supporting the yarn upon its upper nib;

Fig. 3 illustrates the parts shown in Fig. 2 in position with the hook resting against the lower nib just prior to movement of the web holder into its web holding position.

Fig. 4 is a plan view of the web holder ring showing the relation of the presser cams to the web holder cams and adjusting means therefor;

Fig. 5 is a side elevation of the parts shown in Fig. 4 and the contiguous portion of the needle cam;

Fig. 6 is a combined plan and section of the web holder supporting ring and cams for functioning said web holders; and

Fig. 7 is a vertical section on line 7—7 of Fig. 4.

In the drawings, 1 represents a needle carrier of a circular knitting machine, this type of machine being shown merely for convenience as obviously a straight bar or other type of machine may be employed to exemplify features of this invention. Furthermore the present adaptation of the invention is to that class of machines known as spring needle machines wherein the needle carrier and needle functioning elements or cams are given relatively rotary or reciprocatory movement according to the

nature of the work to be produced although clearly latch or other types of needles instead of spring needle may be employed.

For convenience the present example is shown as embodying a needle carrier in the form of a cylinder adapted to receive rotary and reciprocatory motion in a manner characteristic of the Banner type of knitting machine, although it will be readily seen that within the scope and purpose of the invention the needle carrier may be held stationary and the knitting cam or needle functioning means be revolved.

The needle carrier 1 is provided with a series of spring beard needles 2 having the usual movement imparted thereto by stitch cams 3 of any suitable design but herein similar to those employed in the machine of said patent. The means for revolving and reciprocating the needle carrier being old and well known to those skilled in the art further description and illustration thereof is omitted.

Supported upon and movable with the needle carrier 1, is a web holder bed ring 4 having formed in its upper surface radial grooves 5 within which suitable web holders 6 are arranged, said web holders being disposed in the usual manner in alternation with the needles 2. In practically all types of knitting machines capable of producing reciprocating knitting as well as rotary knitting, whether such machine employs latch, spring or other types of needles, considerable difficulty has been experienced in taking care of the long strands of yarn leading from the yarn guides past idle or elevated needles to the active needles, during reciprocating knitting and especially where web holders, sinkers or similar elements are employed, it being desirable to retain the

said long strands of yarn above the web engaging portions of the web holders in order to prevent said yarn from being sunk between the idle needles of the series by said web holders and thereby eliminate all danger of such yarn being ruptured by the action of the web holders during movements thereof to engage the web. In this connection one method of effecting the results above described is to provide the web holders with two nibs, a lower nib 7 and an upper nib 8. The lower nibs 7 perform the functions common to web holders of the ordinary latch or spring needle knitting ma-

chines, but they principally serve as means to cooperate with the needles during their downward movements in measuring the yarn for the new loops. Ordinarily the upper nib 8 is employed in engaging the web when the web holder is advanced to prevent the newly formed loop of said web from being carried upward by the needles while said needles are being raised to yarn receiving positions, said upper nib and said lower nib forming a throat 9 to receive said web during the functioning of said web holders. In order to render the upper nib 8 effective as a yarn supporting element during reciprocating knitting as hereinbefore stated, said web holders are retracted only just far enough to substantially align the extremities of said upper nibs with the outer plane of the shanks of the needles as shown at the left hand side of Fig. 1 and in Fig. 2 so that when the needles are elevated as in Fig. 2 the yarn shown at *a* will be held by said needles upon said upper nibs and be prevented from dropping down against the lower nibs 7 so as to be ruptured when said web holders advance to engage the web.

It will be obvious by referring to Figs. 1 to 3 inclusive that the shank of the needle is much larger in diameter through that portion aligning with said upper nib when the needle is elevated than it is through the portion thereof which aligns with said upper nib when it is approaching its lower position as shown in Fig. 3, the difference in the two portions of said needle being due to the fact that the needle shank within the hook and at its front or outer edge is tapered at 10, away from the beard 11 thereof. Consequently when the thinner portion of said needle is brought into alignment with said upper nib a gap or space 12 will be produced through which the yarn supported by said upper nib may drop to a position against the upper edge of said lower nib 7 in which position it must lie during the yarn measuring and loop forming operations.

The principal objects of the present invention are to provide means for insuring the retraction of said upper nibs each time to the precise position necessary to support said yarn *a* when the needles are raised as in Fig. 2 and at the same time provide means whereby the initial starting points of retraction of said web holders, during alternate movements of the needle carrier, may be varied to correspond with the respective knitting waves of the needles without disturbing the ultimate point of retraction of said web holders. To accomplish the above result I employ the usual cap ring 13 which is mounted upon the web-holder bed-ring 4 and has formed in its under face a suitable channel 14 to receive the upwardly extending butts 15 of the web holders,

shown most clearly in Fig. 6. The greater portion of the channel 14 is arranged concentric with the axis of said needle cylinder and as long as the butts of said web holders remain in this channel no radial movement thereof will take place, and the web holders will remain advanced to their innermost positions.

Mounted upon said ring are web holder advancing and retracting cams which operate to function said web holders in cooperation with the needles during reciprocating or rotary knitting as the case may be. In the copending application hereinbefore referred to as well as in my Patent No. 1,235,545 of August 7, 1917, the retracing cam for said web holders consists of a single cam of sufficient length to function said web holders respectively during alternate movements of the needle carrier while separate advancing cams are disposed in cooperative relation with opposite ends of said retracting cam. The objection to certain retracting cams of the prior art is that it is difficult to adjust opposite ends thereof so as to effect the desired cooperation between the web holders and certain needles of the knitting waves without disturbing the ultimate retracted positions of said web holders necessary to properly support the yarn against the stems of the elevated needles. In the present example I have shown means for retracting said web holders which consists of a central relatively fixed cam member 16 having an outer curved face 17 arranged substantially concentric with the axis of the needle cylinder and at a distance therefrom sufficient, by reason of its engagement with the web-holder butts, to retain said web holders at the desired outer extent of their retraction, said central cam member being preferably formed of hardened steel or other suitable material so as to enable it to withstand the severe action imposed thereon by the revolving web holders.

In addition to said centrally fixed cam said web holder retracting means includes two adjustable wing cams 18 and 19, respectively pivoted at opposite ends of said fixed cam member 17 upon suitable pivots such as screws 20, and having outer curved guiding surfaces 18' and 19' respectively which cooperate with the surface 17 of said central cam to retract said web holders. The ends of said wing cams most remote from said fixed cam member, or in other words, the movable ends thereof are arranged to be adjusted toward and away from the axis of said cam ring by independently adjusting means so as to vary the relation of said ends with respect to the terminal portions of the part of said cam ring forming the inner circular wall of the channel 14, whereby the initial point of retraction of the web holders may be varied. To accomplish the individ-

ual adjustment of said movable cam ends, I have provided herein means consisting of a link 21 arranged against the upper surface of the cap ring 13 and having connection with the movable end of its wing cams by means of a screw 22 which extends through a slot 23 formed in said cap to allow the necessary movement of said cam to take place. The link 21 extends outwardly beyond the periphery of said cap ring and has a depending slotted portion 24. This slotted portion of said link is arranged between shoulders 25 and 26 formed upon an adjusting screw 27 having screw threaded engagement with the adjacent portion of said cap ring. By this arrangement it will be obvious that upon the rotation of the screw 27 in one direction or the other, corresponding movement will be imparted through the screw 22 to the free end of the cam connected with the lower end of said screw and a very accurate and fine adjustment of said cam or cams may be accomplished.

Obviously the screw 22 may, within the scope and purpose of the invention, be alone employed as the locking means for said cam, the same being released slightly when adjustment of said cam is desired and tightened upon the completion of said adjustment so as to clamp the cam connected thereto firmly against the under surface of said cap ring. It is also desirable that the advancing web holder cams be independently adjustable although there is not the necessity for such fine adjustment in connection with the latter as with the retracting cam, however in the present example independently adjustable web holder advancing cams are provided herein consisting of cams 28 and 29 arranged respectively upon the opposite side of the channel 14 adjacent to the free ends of the wing cams 18 and 19, each of said cams having a pivot 30 disposed at a suitable distance from the adjustable end of one of said wing cams. The active ends of said advancing cams are inclined at 31 in the usual manner and these inclined ends are arranged to be moved toward or away from the axis of said ring to any desired point for the purpose of varying the positions of the waves produced by said web holders. As a means for securing the ends of said advancing cams in the desired location I provide a screw 32 for each cam which extends through a slot 33 formed in the cap ring and has screw threaded engagement with said advancing cam whereby, when the proper adjustment has been secured, said screw may be tightened to bind said cam against the under side of said ring and thereby maintain said cam in its adjusted position.

During the operation of the machine the butts of the web holders are brought alternately into contact with the inclined faces

31 of said advancing cams 28 and 29 and are thrown by said inclined surfaces against the portion 34 of the outer surfaces of the adjacent ends of that portion of said cap ring which forms the inner wall of the channel 14, and naturally these portions will be subjected to considerable wear and unless especially prepared will be gouged to such an extent that the paths described by the web holders after leaving said advancing and retracting cams will be very irregular. To obviate this the terminal portions of said ring are constructed of hardened, relatively fixed, steel sections 35 and 36, which extend to points adjacent to the movable ends of the wing cams 18 and 19 respectively, so that all portions of the web holder functioning elements are made of more durable material than are the unexposed portions thereof.

The present arrangement of cams has been described as for the purpose of operating web holders and this is the preferred application thereof although clearly such cams are very well adapted for operating instruments for sinking the yarn between the needles or in fact for any other elements of like nature to which a similar movement is to be imparted.

As previously stated the present embodiment of the machine includes spring needles which require additional instrumentalities for pressing the beards in order to cast the loops therefrom. In the present example I have shown as means for accomplishing this result, individual pressers 37 substantially of the form illustrated in said copending application to which reference may be had for further information concerning functions and operations of the same as they form no part of this invention.

While I have herein shown and described merely for illustrative purposes one specific embodiment of my invention, and have disclosed and discussed in detail the construction and arrangement incidental to such disclosure, it is to be distinctly understood that the invention is limited neither to the mere details or relative arrangement of the parts of the stocking nor the specific application herein shown, but that extensive variations from the illustrations may be made without departing from the principles thereof.

Claims:

1. In combination, a series of needles, web holders or sinkers to cooperate with said needles to hold the web and to support the yarn, a carrier for said needles and said web holders or sinkers, means alternately to function said web holders or sinkers according to the direction of movement of the moving part, including two concentric, fixed, segmental portions, independently adjustable, retracting cams at each end of the inner concentric portion and independently

adjustable advancing cams at each end of the outer concentric portion, and opposed in position to said adjustable retracting cams.

- 5 2. In a knitting mechanism, the combination with a series of knitting needles of a series of web holders, means to retract said web holders including a fixed central cam section, independently adjustable wing cam sections arranged at opposite ends of said fixed cam section; and independently adjustable advancing cams disposed adjacent to the movable ends of said wing cam sections.
- 10 15. 3. In a knitting machine, the combination of radially movable knitting elements, means alternately to function said elements in reciprocating knitting according to the direction of movement thereof, said means including independently adjustable retracting cams, an adjusting screw having spaced shoulders and movable axially in a direction substantially parallel with the plane of movement of said cams; and means operationally connecting one of said cams with the said screw between said shoulders.
- 15 4. In a knitting machine, the combination of a needle cylinder having upright needles, a bed ring outside of and at the upper end 20 of the needle cylinder, radially movable sinkers or web holders mounted in said bed ring to cooperate with the upright needles, a sinker cap ring mounted upon said bed ring outside of and concentric with the needles, and means alternately to function said sinkers or web holders in reciprocating knitting according to the direction of movement thereof, said means including independently adjustable cams, a separate adjusting link for each retracting cam, each of said links overlying said cap ring and exposed for adjustment in such position, and adjusting means for each of said links, said adjusting means being so positioned with 25 respect to the links that the latter are freely exposed at the upper surface of the cap ring for adjustment, said adjusting means being adapted positively to move said links in opposite directions.
- 30 45. 5. In a knitting machine, the combination of radially movable knitting elements, means alternately to function said elements in reciprocating knitting according to the direction of movement thereof, said means including independently adjustable retracting cams, and means individually and positively to control movement of said retracting cams in opposite directions including a separate link attached to said cams respectively, and a screw structurally distinct from each link but having rotatable engagement with the respective link and screw threaded engagement with a fixed member, whereby predetermined movement may be imparted to each link and to the cam pertaining thereto.
- 35 6. In combination with a series of needles, web holders to cooperate with said needles to hold the web and to support the yarn, a carrier for said needles and said web holders, means alternately to function said web holders according to the direction of movement of the moving part, including two concentric, fixed, segmental portions; independently adjustable, retracting cams at each end of the inner concentric portion, a fixed central cam section between said independently adjustable, retracting cams; and independently adjustable, advancing cams at each end of the outer, concentric portion, and opposed in position to said adjustable retracting cams.
- 40 7. In a knitting mechanism, the combination with a series of knitting needles, a corresponding series of web holders cooperating with the needles to hold the web, a carrier for said needles and said web holders, means alternately to function said web holders according to the direction of movement of the moving part including two concentric, fixed, segmental portions, independently adjustable, retracting cams at each end of the inner concentric portion, independent means for respectively adjusting said retracting cams and independently adjustable advancing cams at each end of the outer concentric portion and opposed in position to said adjustable retracting cams.
- 45 In testimony whereof, I have signed my name to this specification.

GEORGE PLINEY BOSWORTH.
